Atty's:

UNITED STATES PATENT OFFICE.

JOSEPH REIF, OF HEBRON, INDIANA, ASSIGNOR OF FORTY-FIVE PER CENT. TO
FRANCIS E. LING, OF HEBRON, INDIANA.

CAR-COUPING.

1,397,781.

Specification of Letters Patent. Patented Nov. 22, 1921.

Application filed June 1, 1920. Serial No. 385,485.

To all whom it may concern:

Be it known that I, JOSEPH REIF, a citizen of the United States, residing at Hebron, county of Porter, and State of Indiana, have 5 invented certain new and useful Improvements in Car-Couplings, of which I do declare the following to be a full, clear, and exact description, reference being had to the accompanying drawings, forming a part of 10 this specification.

My present invention has for its object to provide an improved construction of car coupler and the invention consists in the features of novelty hereinafter described, illustrated in the accompanying drawing and particularly pointed out in the claims at the end of the specification.

Figure 1 is a plan view showing a pair of draw heads embodying my invention and 20 showing, also, portions of cars coupled together thereby. Fig. 2 is a view in side elevation. Fig. 3 is a view similar to Fig. 2 showing the parts in different position. Fig. 4 is an end view of my improved coupling. 25 Fig. 5 is a view in cross section on line 5-5 of Fig. 2. Fig. 6 is a view in vertical section at one side of the gravitating latch, parts being shown in elevation. Fig. 7 is a detail perspective view of the gravitating latch.

30 In Figs. 1 and 2 of the drawings, two draw heads designated as A and A' are shown coupled together and as embodying my invention. As these draw heads are duplicates one of the other, a description of one will answer for both. Each of the draw heads is preferably formed of a casting having connected thereto a draw bar a of any appropriate construction and suitably connected with the platform or underframe of the car.

40 In the preferred form of my invention, each draw head comprises a forwardly projecting hook 10 having a rounded end and having an inwardly extending shoulder 11, there being formed at the base of each hook 10 an 45 open space 12 to admit the hook of the companion draw head. As shown, each draw head is formed at the side opposite the hook 10 with a forwardly projecting arm or side portion 13 having a vertically inclined slot 50 formed therein to receive a headed pin 16 the inner end of which is secured to the 55 gravitating latch B. To the pin 16 is pivotally connected a link 17 to the inner end of which is fastened a chain 18. The upper end of this chain is secured to the arm 19 of

a releasing bar 20. This releasing bar 20 is shown as extending from side to side of the car platform C and as having its ends journaled in plates D that are secured to the ends of the platform C, the upper ends of 60 the plates D rising slightly above the platform C. The outer ends of the releasing bar 20 are provided with crank handles 22 by manipulating which crank handles the operator can lift the latch B without passing 65 between the cars. As shown, each of the plates D has a shoulder d offset therefrom at a slight distance from its upper end and against the inclined portion of this shoulder d the crank handles 22 will ride and when 70 these handles are swung from the position shown in Fig. 2 to the position shown in Fig. 3 of the drawings, the elasticity of the metal of the plates D and handles 22 will permit the handles to swing past the shoulders d of 75 the plates D and the shoulders will thus retain the handles in the position shown in Fig. 3 of the drawings, with the latch B lifted.

By reference more particularly to Fig. 7 80 of the drawings, it will be seen that the latch B is of plate-like form and the front edge of the latch B is provided with a beveled or inclined surface 25 upon its inner side, this surface 25 tapering inwardly and downwardly as shown, so that when the rounded end of the hook 10 of one draw head contacts with the inclined surface 25 of the latch of the companion draw head, the latch B will be lifted and at the same time will be moved 85 inwardly from the position shown by full lines to the position shown by dotted lines in Fig. 6. The rear edge of the latch B is formed with an inclined surface 26 adapted to ride upon a correspondingly inclined surface or way 27 that is formed upon the draw head at one side of the space 12 and between said space 12 and the side wall or arm 13 of the draw head and at the upper end of the inclined way or surface 27 is provided a shoulder 28 that may be engaged by the shoulder 29 formed on the latch B to limit the upward movement of the latch. 90 100

From the foregoing description, the operation of my improved coupler will be seen 105 to be as follows, it being understood that the draw heads A, A' are so mounted as to have slight lateral movement: When the draw heads A and A' are brought together to couple the cars, the impact of the rounded 110

portions of the hooks 10 against the inclined portions 25 of the latches B will cause the latches to be lifted and moved rearwardly, as indicated by dotted lines in Fig. 6, until 5 the hooks 10 are within the spaces 12 of the draw heads and the shoulders 11 of the hooks are interlocked, as shown in Fig. 1 of the drawings. When the uncoupling of the cars is to be effected, the operator by turning 10 the crank handles 22 at the sides of the car, can lift the latches B, thus permitting the hooks 10 of the draw heads to be disengaged as the cars are pulled apart, the beveled opposing faces of the shoulders 11 of the hooks 15 readily permitting this disengagement of the hooks 10.

My invention affords an extremely simple, cheap, durable and effective construction of coupler. I wish it understood that the 20 details of construction above set out may be varied without departing from the spirit of the invention and that features of the invention may be employed without its adoption as an entirety.

25 Having thus described my invention, what I claim as new and desire to secure by Letters Patent is:—

1. A car coupler comprising a draw head having a vertically disposed, forwardly projecting hook and a vertically slidable gravitating latch substantially opposite the face of the hook to act upon the opposite side of the corresponding hook on an opposing coupler from the first mentioned hook.

35 2. A car coupler comprising a draw head having a vertically disposed, forwardly projecting hook and having opposite and spaced from said hook a vertically moving gravitating latch, said latch having its front edge 40 beveled upon its inner side.

3. A car coupler comprising a draw head

having at one side a vertically disposed, forwardly projecting hook and having at its opposite side a forwardly projecting arm, and a vertically slidable latch connected to 45 the inner side of said arm substantially opposite the face of said hook and adapted to hold an engaging hook in place when two draw heads are coupled together.

4. A car coupler comprising a draw head 50 having at one side a vertically disposed, forwardly projecting hook and having at its opposite side a forwardly projecting slotted arm, a vertically slidable gravitating latch connected to the inner side of said arm sub- 55 stantially opposite the face of said hook and adapted to hold an engaging hook in place when two draw heads are coupled together, and a guide pin extending through said slotted arm and connected to said latch. 60

5. A car coupler comprising a draw head having a vertically disposed, forwardly projecting hook and a vertically slidable gravitating latch spaced from said hook to act 65 upon the opposite side of the corresponding hook on an opposing coupler from the first mentioned hook, said draw head being provided with an inclined way along which the latch may slide vertically and rearwardly when pressure is exerted upon the front edge 70 of the latch.

6. A car coupler comprising a draw head having a vertically disposed, forwardly projecting hook and a vertically slidable gravitating latch spaced from said hook to act 75 upon the opposite side of the corresponding hook on an opposing coupler, from the first mentioned hook, an operating rod for lifting said latch, and means connecting said rod to said latch.

JOSEPH REIF.
